UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

VARIABLE THREAD-CONTROLLING MECHANISM FOR SEWING-MACHINES.

1,277,250.

Specification of Letters Patent. Patented Aug. 27, 1918.

Application filed May 24, 1916. Serial No. 99,622.

To all whom it may concern:

Be it known that I, LANSING ONDERDONK, a citizen of the United States, residing at New York, in the county of New York, State of New York, have invented certain new and useful Improvements in Variable Thread-Controlling Mechanisms for Sewing-Machines, of which the following is a description; reference being had to the accompanying drawing and to the figures of reference marked thereon.

The invention relates to new and useful improvements in variable thread controlling mechanisms for sewing machines, and more particularly to a thread controlling mechanism for the looper thread in a chain stitch sewing machine.

An object of the invention is to provide a thread controlling mechanism wherein two thread engaging devices may be given a differential movement relative to each other in certain timed relation to the movement of the loopers for giving up and taking up thread in addition to their bodily travel in the same direction to give up and take up thread.

A further object of the invention is to provide means whereby the differential movement of said thread engaging devices relative to each other may be varied.

These and other objects will in part be obvious and will in part be hereinafter more fully described.

In the drawings, which show by way of illustration one embodiment of the invention:

Figure 1 is a view, in front elevation, showing a machine having my improved thread controlling mechanism applied thereto, the work support being removed;

Fig. 2 is a view, partly in plan and partly in section, of the parts beneath the work support;

Fig. 3 is a detail, partly in section and partly in front elevation, showing on an enlarged scale my improved thread controlling device;

Fig. 4 is a perspective view of the active elements of the thread controlling device;

Fig. 5 is a detail in plan showing the operating lever, the operating rock shaft, and the means for actuating the same from said lever;

Fig. 6 is a detail, partly in side elevation

and partly in section, showing the bed plate, the rock shaft, and the devices for operating the looper support therefrom;

Fig. 7 is a detail showing the operating arm for actuating the looper support in plan;

Fig. 8 is a view showing, more or less diagrammatically, the work support, the looper and the needle, the looper being at the rear end of its stroke in full lines and at the forward end of its stroke in dotted lines;

Fig. 9 is a view showing, more or less diagrammatically, the position of the thread controlling elements when the looper is at the rear end of its stroke;

Fig. 10 is a similar view showing the thread engaging devices having finished their differential movement and moving bodily together, the looper at the point having just well entered the needle thread loop;

Fig. 11 is a similar view with the looper at the forward end of its stroke and the thread controlling elements having completed their movement.

The improved thread controlling mechanism is especially adapted for a looper which moves back and forth in the general direction of the line of feed when entering and leaving the needle thread loop. The thread supply is from a direction at right angles to the travel of the looper and as a consequence the first part of the forward movement of the looper gives slack to the thread very rapidly. It is essential, therefore, that the thread controlling mechanism should be so constructed as to take up thread during the first part of the forward movement of the looper. After the looper point has entered the needle thread loop then

thread should be given to the looper to prevent the breaking of the looper thread during the last part of the forward movement of the looper. It is essential also, therefore, that the thread controlling mechanism should be so constructed as to give up thread at this time. On the first part of the backward movement of the looper, the looper thread should be held substantially taut until the point of the needle passes between the looper thread and the body of the looper, but after the needle loop has been shed from the looper, thread should then be given to the looper so that the stitches may be drawn

up and set without having the looper pull its thread against the needle. It is again essential that this thread controlling mechanism should maintain the thread substantially taut as the looper starts back and then finally give up thread to the looper.

In order to accomplish this controlling of the thread, I have provided two thread engaging devices which are capable of moving bodily together for giving up and taking up thread and which are also capable of having a differential movement relative to each other for giving up and taking up thread.

Referring more in detail to the drawings, I have shown my improved thread controlling devices as applied to a sewing machine having a supporting bed 1 on which is mounted an overhanging arm 2. The needle bar 3 reciprocating in the outer end of the overhanging arm is provided with a plurality of needles 4. The needle bar is reciprocated by a needle lever 5 which is pivoted at 6 to the overhanging arm, and said needle bar 3 is oscillated by an eccentric strap 7 coöperating with an eccentric on the main shaft 8. Said eccentric strap 7 is pivotally connected to a ball stud 9 on the needle lever.

Coöperating with each needle beneath the work support is a looper 10. These loopers are mounted on a looper carrier 11 which, in turn, is mounted on a looper support 12. The looper support is in the form of a shaft and is mounted to oscillate and slide endwise in bearings 21 and 22. On the extreme inner end of the looper support 12 is a sleeve 23 carrying a head 24 in which is slidably mounted a pin 25 having a ball 26 on its outer end. This ball 26 is adapted to be connected to an arm 27 carried by a rock shaft 28. The rock shaft is mounted on a stud 29 clamped to the supporting bed 1. The rock shaft is also provided with an arm 30. This arm is connected to a lever 31 by a link 32. The lever 31 is oscillated by an eccentric 33 which coöperates with an eccentric on the main shaft 8. This looper mechanism *per se* forms no part of the present invention, but is shown, described and claimed in my co-pending application, Serial No. 99620, filed of even date herewith.

The looper mechanism, however, has been described sufficiently in detail so that it will be understood that the loopers are moved back and forth in the general direction of the line of feed. The looper support is moved endwise as well as oscillated, and the train of mechanism referred to above is so constructed as to move the looper in a forward direction while little or no lateral movement until after the point of the looper has well entered into the needle loop, after which the looper is moved laterally to the end of its stroke. At the forward end of its stroke, the speed travel of the looper

is reduced, and the looper may be given an extended dwell. This is brought about through the lever 31 and the link which is operated thereby, moving into alinement or slightly by such alinement. The looper is first retracted very slowly so that the needle will pass the looper thread which is held on the opposite side of the path of the needle, from that passed by the looper when moving forward, after which the looper is retracted sufficiently and moved laterally to permit the needle to pass between the thread and the body of the looper.

The looper threads are indicated at 7. There is a separate looper thread for each looper. My improved thread controlling mechanism for the looper threads operates in precisely the same way for each looper and for the sake of clearness will be described as operating upon a single thread. The looper thread is led from the supply through a suitable tension T, and thence through a thread guide 35. After leaping the thread guide 35, the looper thread passes through a thread eye formed in an arm 37 fixed to a shaft 38 which is mounted to oscillate in a supporting bracket 39. This supporting bracket 39 is secured to the bed plate 1 by screws 40 which pass through elongated slots in the bracket, thus permitting the bracket to be adjusted in the direction of its length or toward and from the looper. The looper thread passes through the guiding eye 36, thence around a pin 41 mounted on an arm 42 which is adjustably attached to the needle lever extension 43. The shank of the arm 42 is slotted at 44, and a screw 45 passing through said slot and into said lever extension holds the arm in an adjusted position. This permits this arm to be adjusted toward and from the looper. The thread 7 after passing around the pin 41 passes back again through the thread guide eye 36, and thence under an arm 46 carried by the bracket 47, over an arm 48 carried by the bed plate 1; through a guiding slot 49 in a bracket on the bed plate, and under a guiding pin 50; through a guide eye 51 mounted at the end of the looper carrier, and from this guide eye 51 the thread is led directly to the looper. The shaft 38 is oscillated by a link 52 which is pivoted at 53 to the needle lever extension 43. Said link 52 is pivoted at 54 to an arm 55 fixed to the shaft 38.

From the above, it will be apparent that, when the needle lever extension 43 is oscillated, both the arm 37 and the arm 42, that is, the thread engaging devices, will move bodily toward and from the looper, giving up and taking up thread. It will also be apparent that, when the arm 37 is moved to its extreme right hand position, as shown in Fig. 9, the link 52 and the needle lever extension 43 are substantially in aline-

ment. This results in the following action upon the thread engaging devices: When the parts are first moving from the position shown in Fig. 9, the thread arm 42 moves 5 forward with the needle lever extension, while there is very little or no movement given to the arm 37 owing to the fact that the link 52 is substantially in alignment with the needle lever extension 43. This results 10 in the pin 41 moving away from the thread eye 36, and a drawing on the thread to take up the slack on the thread between the looper and the thread supply. In Fig. 9, I have shown the looper at the rear end of 15 its stroke, and as it moves forward, the forward movement of the pin 41 relative to the arm 37 takes up the slack given up by the looper. This prevents the forming of slack thread in front of the eye of the looper 20 which might cause the kinking of the thread or the wiping of the looper thread around the looper or a shoving of the needle thread loop to one side and preventing the looper from entering the needle loop. As soon as 25 the looper point is well into the needle loop, the link 52 reaches a position so as to oscillate the arm 37 in substantially the same timing as the movement of the arm 42. This position of the parts is shown in Fig. 10. 30 From this time on or until the looper reaches the forward end of its stroke, the arm 36 and the arm 42 are moving toward the looper bodily together and giving up enough thread which permits the looper thread to 35 be free from tension when the stitch is set, thereby causing the looper thread loop in the stitch to be relatively long and lie flat against the under surface of the fabric. When the looper begins its backward movement, both the arm 42 and the arm 37 move 40 rearwardly together, taking up the slack in the looper thread caused by the backward movement of the looper, and this holds the looper thread taut so that the needle will 45 with certainty pass between the looper thread and the body of the looper. After the needle has gotten well down past the looper thread, the arm 37 has reached the rear end of its stroke and the arm 42 moving 50 toward the arm 37 gives up thread to the looper, permitting it to move freely back to the rear end of its stroke.

From the above description, it will be apparent that I have provided a thread controlling mechanism for the looper thread wherein the thread engaging elements move bodily back and forth to take up and give 55 up looper thread, and wherein one of the elements moves relative to the other to give up and take up thread. By adjusting the position of the bracket 39, the amount of dwell given to the thread arm 37 may be varied. Thus the amount of thread pulled up by the differential movement between the 60 two arms 42 and 37 vary. The arm 42 may

be adjusted so as to permit the adjustment of the bracket 39 and so as to properly position the arm 42 relative to the arm 37.

Having thus described the invention, what is claimed as new is:—

1. The combination with a looper moving in the general direction of the line of feed, of a thread controlling mechanism therefor, including two thread engaging elements and devices for moving said elements bodily in 75 the same direction for taking up looper thread and in the opposite direction for giving up looper thread, said devices having means for moving one of said elements relative to the other during said taking up action for giving up thread, and during said giving up action for taking up thread.

2. A looper thread controlling mechanism including in combination two movable thread arms, and devices for moving said 85 thread arms to give up thread to the looper on its forward stroke, said devices including means for moving one thread arm relative to the other to take up looper thread on the first part of said forward stroke.

3. A looper thread controlling mechanism for sewing machines including two thread arms, and devices for moving said thread arms in the same direction for taking up looper thread on the backward movement of the looper, and said devices including means for moving one of said arms relative to the other to give up thread during the backward movement of the looper.

4. A looper thread controlling mechanism 100 for sewing machines including in combination, two thread arms, and means for moving one thread arm relative to the other for taking up thread on the first part of the forward movement of the looper for substantially moving said arms together to give up thread to the looper as it completes its forward movement.

5. A looper thread controlling mechanism for sewing machines including in combination, two thread arms, and means for moving one thread arm relative to the other for taking up thread on the first part of the forward movement of the looper for substantially moving said arms together to give up 110 thread to the looper as it completes its forward movement, and for moving said thread arms for taking up thread on the first part of the backward movement of the loopers and for subsequently moving said arms relative to each other for giving up looper thread as the looper moves to the rear end of its stroke.

6. A looper thread controlling mechanism for sewing machines including in combination, a thread arm, a shaft supporting said arm, an oscillating lever, a thread arm carried thereby, a link connecting said lever to said shaft whereby the shaft is oscillated by said lever, said link 125

and lever being so constructed and arranged as to move into alinement to give a dwell to the shaft, whereby said thread arms may have a relative movement and a 5 bodily movement together as the lever moves in either direction.

7. A looper thread controlling mechanism for sewing machines including in combination, a thread arm, a shaft supporting said arm, an oscillating lever, a thread arm carried thereby, a link connecting said lever to said shaft whereby the shaft is oscillated by said lever, said link and lever being so constructed and arranged as to 10 move into alinement to give a dwell to the 15

shaft, whereby said thread arms may have a relative movement and a bodily movement together as the lever moves in either direction, a bracket for supporting said shaft, and means for adjusting the position 20 of the bracket in the plane of oscillation of the lever whereby the differential movement imparted to the thread arms may be varied.

In testimony whereof, I affix my signature, in the presence of two witnesses.
